United States Patent Office

Des. 189,079
Patented Oct. 18, 1960

189,079

ELEVATED TANK

Lloyd E. Anderson, Pittsburgh, Pa., assignor to Pittsburgh-Des Moines Steel Company, Pittsburgh, Pa., a corporation of Pennsylvania

Filed Sept. 9, 1959, Ser. No. 57,486

Term of patent 14 years

(Cl. D91—1)

The figure is a perspective of an elevated tank showing by new design.

The sides of the elevated tank not shown are substantially the same in appearance as the side shown.

I claim:

The ornamental design for an elevated tank, as shown and described.
